UNITED STATES PATENT OFFICE.

ANDRÉ LENIEF, OF PARIS, FRANCE.

TOOTHEBRUSH.

Application filed October 16, 1922. Serial No. 594,841.

To all whom it may concern:

Be it known that I, ANDRÉ LENIEF, a citizen of the Republic of France, and resident at Paris, France, have invented new and useful Toothbrushes, which toothbrush is fully set forth in the following specification.

The present invention relates to toothbrushes; and its object, briefly stated, is the provision of an article of the character indicated embodying a bristle-carrying member or brush proper which may be readily detached when the bristles become worn and replaced by a new one, the invention residing primarily in the improved means or devices employed to retain the bristle-carrying member in place.

Referring more particularly to the accompanying drawing,

20 Figure 1 is a part-sectional side elevation of one form which the invention may take in practice.

Fig. 2 is a front view thereof, also partly in section, but with the brush proper omitted and the head and the adjacent part or member of the handle separated from the other part or member of the handle.

As represented in said drawing, the improved brush embodies a handle 1 and a head or holder; the latter being indicated generally at 10 and being provided with a recess 11 to conformably and removably receive therein the back 5 of the bristle-carrying member or brush proper.

35 The handle 1 is structurally separate from and capable of rotation with relation to the shank 4 of the head. The inner

end of the handle has attached to it a threaded stem 2, forming a locking element and terminating in a point 3; said stem 40 adapted to be screwed into a threaded axial passage 12 in the shank 4 which opens through the wall of the brush-holding recess 11. The brush back 5 has formed in its circumferential wall, at one end of its median line, a hole or seat 7 to receive a lateral spur 8 on the wall of recess 11; and at the other end of its said median line it is formed with a hole or seat 6 registering with the open end of the threaded passage 12. 45 50

I claim as my invention:

A brush, comprising a head provided with a brush-holding recess; a shank rigidly connected to the head and having a threaded axial passage opening at its inner end directly through the wall of said recess and at its outer end through the free end of the shank, said wall being provided with a lateral spur which is located diametrically opposite the inner end of said passage; a brush 55 60 having its back conformably and removably fitting in said recess and provided at one end with a seat to receive said spur and at the other end with a seat in register with said inner passage end; a removable handle; and a threaded locking stem fixed to the inner end of the handle for engagement in said passage and terminating in a point which projects through the inner passage end into the second-named seat. 65 70

In testimony whereof I have signed this specification.

ANDRÉ LENIEF.
